UNITED STATES PATENT OFFICE.

LOUIS KELLNER, OF BROOKLYN, NEW YORK.

ELECTRIC SWITCH.

1,354,758.

Specification of Letters Patent.

Patented Oct. 5, 1920.

Application filed December 3, 1917. Serial No. 205,139.

To all whom it may concern:

Be it known that I, LOUIS KELLNER, a citizen of the United States, and a resident of the borough of Brooklyn, county of 5 Kings, city and State of New York, have invented certain new and useful Improvements in Electric Switches, of which the following is a specification.

This invention relates to improvements in 10 manually operable electric switches.

One of the principal objects of the invention is to provide a switch having a reciprocable contact-carrying member adapted to be reciprocated with a rapid or snap action 15 to make and break the circuit upon swinging or rotating an operating lever or switch handle.

A further object is to provide means whereby the reciprocable contact-carrying 20 member will only be shifted when the actuating lever has been moved to substantially the limit of its throw, thus preventing accidental making or breaking of the circuit through an accidental or careless movement 25 of the switch lever.

A further important object of the invention is to provide a switch so constructed and arranged that access to the fuse plugs is impossible except when the switch has 30 been operated to break the circuit.

A further object of the invention is to provide a switch having a reciprocable contact and fuse plug carrying member operable with a snap action by a swinging lever, 35 the entire switch being inclosed within a casing having a cover permitting access to the switch lever, and the fuse plugs being inclosed within an inner casing held to the reciprocable member, the inner and outer 40 casings being so constructed that the inner casing can only be opened when the switch lever has been swung to break the circuit.

In the drawings, Figure 1 is a longitudinal sectional view of the switch taken on the 45 line I—I of Fig. 4;

Fig. 2 a sectional plan taken on the line II—II of Fig. 1;

Fig. 3 a longitudinal section on the line 50 III—III of Fig. 4, the parts being shown in position to close the circuit;

Fig. 4 a vertical central transverse section, the parts being shown in position to break the circuit;

Fig. 5 a fragmentary sectional plan taken 55 through the fuse box;

Figs. 6, 7 and 8 are fragmentary sec-

tional views showing the positions assumed by the operating mechanism when the switch lever has been moved to break the circuit, when the lever is in an intermediate 60 position, and when the lever has been moved to close the circuit, respectively;

Fig. 9 a fragmentary vertical section showing the rack and segment for shifting the reciprocable switch member; 65

Figs. 10 and 11 detail views of a part of the operating mechanism;

Figs. 12 and 13 detail views of another part of the operating mechanism, and Fig. 14 a detail view illustrating the operation 70 of setting the latch-releasing device 45 during an initial movement of the operating handle.

Referring to the various parts by numerals, the switch is mounted on a suitable 75 base 1, which may be formed of porcelain or other suitable material, and the entire switch mechanism is inclosed within a box-like outer casing, preferably formed of sheet metal and held to the base 1 in any 80 suitable manner. The casing is formed with side walls 2, end walls 3, and a cover 4 hinged to one of the end walls at 5.

Two vertically extending frame members or plates 6 and 7 are held at their lower ends 85 substantially centrally of the base 1, said members being preferably connected by an integral base plate 8 fastened upon the upper face of the base 1 by suitable screws 9. The frame plates 6 and 7 are connected adjacent 90 their upper ends by a rod 10 on which is rotatably mounted a sleeve 11 having reduced angular end portions 12 and 13. The sleeve 11 is adapted to be oscillated by a swinging switch handle or lever 14 having 95 an angular opening or socket through which the reduced end portion 12 of the sleeve extends. A disk 15 is mounted on the reduced angular end portion 13 of sleeve 11, said disk being formed with a central 100 angular opening 16 through which said end portion 13 extends to adapt the disk to rotate with said sleeve. The disk 15 is cut away through slightly more than half its periphery to form stop shoulders 17 and 18 105 adapted to abut against the free end of a pivoted arm or latch 19 when the switch lever is swung to the limit of its throw to break and close the circuit, respectively.

The latch 19 is pivotally held at 20 to a lug 110 21 stamped inwardly from the frame plate 6, and is normally pressed upwardly in the

path of the stop shoulders 17 and 18 by a suitable flat spring 22 held to the frame member 6.

A disk 23 is loosely mounted on the rod 10 adjacent the outer face of disk 15, and a mutilated gear wheel or segment 24 is held to the outer face of disk 23 to rotate therewith by means of suitable pins or rivets 25. The teeth of the gear wheel 24 mesh with the teeth of a rack 26 formed at one side of a vertically extending elongated opening 27 in a bracket 28. The bracket or plate 28 is held at its lower end by screws 29, to the upper face of a reciprocable block 30 formed of insulating material. The block 30 and bracket 28 are guided vertically, the block being provided with openings 31 through which the frame plates 6 and 7 extend, and the bracket being provided with an outwardly projecting pin or lug 32 working in an elongated slot 33 formed in the frame plate 7. The pin 32 serves also to limit the upward movement of the block 30 and the parts mounted thereon.

25 A spring 34 is coiled about the sleeve 11 and the opposite ends 35 and 36 of said spring project outwardly at one side of the sleeve in different horizontal planes. The switch lever 14 is provided with an inwardly projecting pin 37 extending between the ends 35 and 36 of spring 34, and the disk 23 is provided with an oppositely projecting pin 38 extending between the ends of said spring. The disk 23 is cut away through slightly more than half its periphery to form stop shoulders 39 and 40 adapted to engage latch 19 in the same manner as shoulders 17 and 18 of disk 15, and said disk 23 is also formed with oppositely disposed notches 41 and 42 in which the upper edge of latch 19 is adapted to engage to hold the disk 23 against rotation until the latch is released as hereinafter described. The latch 19 is adapted to be disengaged from notch 41 and notch 42 by the inclined or cam-shaped ends 43 and 44 of an arcuate oscillating releasing member 45 pivotally held at 46 to the inner face of disk 15. The disk 15 is provided with two lugs or stop pins 47 and 48 and the arcuate releasing member 45 is adapted to be rocked about its pivot 46 and held against said stop pins alternately to alternately project the cam ends 43 and 44, respectively, beyond the periphery of the cut-away portion of disk 15 in position to depress latch 19 and disengage said latch from notches 41 and 42 in disk 23, as hereinafter described. The member 45 is adapted to be held against either of the stops 47 and 48 by a flat spring 49 held at one end to disk 15 in any suitable manner and formed with an offset portion 50 adapted to engage against opposite sides of a projection 51 formed on the member 45 adjacent the pivot 46 of said member.

A pair of fuse plugs 52 of well-known construction are supported on the block 30, the opposite ends of said plugs being detachably held in two pairs of suitable spring metal clips 53 and 54. Two pairs of contact brushes 55 and 56 are held to the under side of block 30 and electrically connected with the pairs of fuse-holding clips 53 and 54, respectively, by screws or bolts 57 and 58, the ends of the brushes preferably fitting in cut-away portions of the block 30, as shown. The outer ends of the brushes 55 are adapted to engage with contacts 59 held to the base 1, and the ends of brushes 56 are adapted to engage contacts 60 held to said base to complete the circuit through the switch when block 30 is depressed, as hereinafter described.

The fuse plugs 52 are inclosed within a divided inner casing, the two halves 61 and 62 of which are hinged to rods 63 and 64 supported in the opposite ends of a pair of bars 65, preferably countersunk in opposite sides of block 30 and held thereto by screws 66. The parts 61 and 62 of the casing may be provided with interlocking portions or latches 67, if desired. The outer casing is divided into upper and lower compartments by a false bottom or horizontally extending partition 68 having a central opening 69 therethrough to permit the passage of the fuse casing and block 30 through said partition when the switch lever 14 is operated, as more fully hereinafter described.

To operate the switch to close the circuit, the switch lever 14 is swung through an arc of substantially 180° from the position shown in Figs. 1 and 2 to the position shown in Fig. 3. Referring more particularly to Figs. 6 to 9, it will be observed that as the lever 14 is thrown over, the sleeve 11 and disk 15 are rotated in a clockwise direction while disk 23 is held stationary by latch 19 which is engaged in notch 41 in disk 23, and it will also be seen that spring 34 is wound or placed under tension by pin 37 on lever 14, which forces the end 35 of said spring before it as the lever is swung to the right. It will be observed also that the inclined or cam end 44 of releasing member 45 is in projected position with its rear face 44a in position to engage latch 19 during the initial movement of the switch handle. As the rear face 44a rides over latch 19 the releasing member 45 will be rocked about its pivot 46, as spring 22 is stronger than spring 49, thus forcing the projection 51 to the opposite side of projection 50 on spring 49, retracting cam end 44 and projecting cam end 43 beyond the periphery of disk 15 in position to engage latch 19 and depress the same when the switch handle approaches the limit of its throw. As the lever 14 approaches the limit of its throw the inclined end 43 of

releasing member 45 engages latch 19, as shown in Fig. 7, depressing said latch and releasing disk 23 which is rapidly rotated in a clockwise direction by reason of the 5 engagement of the end 36 of spring 34 under pin 38 on disk 23. The rapid movement of disk 23 imparts a similar rapid semi-revolution to the mutilated gear or segment 24 meshing with rack 26, thus rapidly 10 projecting or forcing bracket 28, block 30, and parts carried thereby, downwardly into the position shown in Figs. 3 and 8, in which position the pairs of brushes 55 and 56 engage the pairs of contacts 59 and 60 15 and close the circuit through the switch. The latch 19 is preferably beveled at each side of its upper edge at the points where said latch is engaged by the cam ends of the releasing member 45 to form a cam surface 20 70 having its apex or highest point substantially centrally of the upper edge of the latch. It will thus be seen that it is practically impossible for the switch lever to be held or to remain in a position to hold 25 the latch 19 in its fully depressed or releasing position as the high point or rear end of cam end 44 cannot be held or dwell upon the apex of the cam portion 70 of the latch. It will be seen, therefore, that the instant 30 disk 23 is moved through half a revolution as above described to force the laminated spring-metal contacts 55 and 56 into close engagement with the contacts 59 and 60, the latch 19 will snap into notch 42 in 35 disk 23 and positively lock said disk against rotation. This construction is especially advantageous since the locking device is free to act instantly upon the completion of the circuit-closing movement, independently of 40 any subsequent movement of the switch handle, thus positively locking the actuating mechanism against rebounding or a return movement under the influence of back pressure due to compression of the spring 45 contacts 55 and 56. This is a feature of importance, not only because it insures holding the contacts in firm engagement, but also because it insures locking of the mechanism in order to enable power to be 50 stored for a subsequent operation of the switch handle to break the circuit with a snap action, and prevents rebounding or reverse rotation of the parts to a point at which the locking mechanism cannot act. 55 At the completion of the circuit-closing operation just described the parts assume the position shown in Fig. 8, with the rear edge 43^a of a cam end 43 projected into position to engage and ride over latch 19 during 60 the initial movement of the switch handle toward the left to break the circuit. The circuit-breaking operation is the reverse of the operation just described and is thought to be obvious. 65 From the foregoing it will be observed

that the switch lever may be swung substantially the full length of its throw without moving the brush-carrying block 30; that the movable contact member is operated with a rapid reciprocatory snap action to close the circuit as well as to break the circuit; and that the entire switch mechanism is inclosed within a protecting casing. 70

It will also be seen that the fuse plugs are inclosed in a box or casing which is shifted 75 into the lower compartment of the switch casing when the circuit is closed, and that the fuse box is so constructed that the hinged covers or sections thereof cannot be swung upwardly to permit access to the 80 fuses when the circuit is closed, the false bottom 68 being so positioned as to prevent the hinged sections 61 and 62 of the fuse box from being swung upwardly and outwardly except when the switch is in "off" 85 position as shown in Figs. 1, 2 and 4, in which position the fuse box is projected above the false bottom or partition 68. It will be noted further that the switch cannot be moved to "on" position with the 90 hinged sections of the fuse box in open position as said sections will be swung upwardly and inwardly to closed position when the block 30 moves downwardly by reason of the engagement of the partition 95 68 with the end walls of said sections, as indicated in dotted lines in Fig. 1. The cover 4 of the outer casing may also be provided with a suitable locking means to prevent unauthorized access to the switch lever 100 14, if desired.

It will also be observed that the operating mechanism is positively locked immediately upon the completion of its movement in either direction to prevent rebounding and 105 to insure the setting or locking of the parts in position to perform a subsequent operation.

What I claim is:

1. In an electric switch, the combination of 110 stationary contacts, movable contact-bridging means, a rotary element operatively connected to shift the contact-bridging means into engagement with the stationary contacts when rotated in one direction and to 115 shift said means to break the circuit when rotated in the opposite direction, a coiled spring having laterally projecting end portions, an arm on said rotary element extending between the end portions of the spring, 120 a switch handle capable of rotary movement in either direction independently of said element, an arm on said handle extending between the ends of the spring, a spring pressed latch for automatically locking said 125 rotary element in both its "on" and "off" positions, and means operable by said handle for releasing said latch after a predetermined movement of the handle in either direction.

2. In an electric switch, the combination of stationary contacts, movable contact-bridging means, an element rotatable in opposite directions and operatively connected to shift said bridging means to "on" and "off" position, a handle rotatable in opposite directions independently of said element, a coiled motor spring having projecting ends, arms carried by said element and handle extending between the ends of the spring, means for automatically locking said element against rotation in both its "on" and "off" positions, and means rotatable with said handle adjustable relatively thereto and automatically set upon an initial movement of the handle in either direction in a position to release said locking means after a predetermined additional movement of the handle.
3. In an electric switch, the combination of stationary contacts, movable contact-bridging means, an element rotatable in opposite directions and operatively connected to shift the bridging means to "on" and "off" positions, said element being formed with two spaced recesses, a spring pressed latch adapted to engage in said recesses alternately, a handle rotatable in opposite directions independently of said element, a coiled motor spring having projecting ends, arms carried by said element and handle extending between the ends of the spring, a rockable releasing device rotatable with said handle one end of which is adapted to release said latch from one of said notches and the other end of which is adapted to release the latch from the other of said notches, and means for rocking said device upon an initial movement of the handle to position the same to release the latch after a predetermined movement of the handle.
4. In an electric switch, the combination of stationary contacts, movable contact-bridging means, an element rotatable in opposite directions for shifting said bridging means to "on" and "off" positions, a motor spring, a switch handle rotatable in opposite directions to store power in said spring to rotate said element, a latch for locking said element against rotation, a latch releasing device movable with the handle and shiftable relatively thereto, and means whereby said releasing device is shifted relatively to the handle by engagement with said latch during the initial movement of the handle into position to release said latch after a predetermined additional movement thereof with the handle.
5. In an electric switch, the combination of stationary contacts, contact-bridging means, a rack held to said bridging means, a pinion meshing with said rack, a coiled spring, a handle rotatable in opposite directions independently of said pinion, means for automatically locking said pinion against

rotation in both the "on" and "off" positions of said bridging means, connections between said spring and the handle and pinion for storing power in said spring for rotating the pinion in the direction of movement of the handle, and means movable with the handle for releasing the pinion after a predetermined movement of the handle in either direction.

6. In an electric switch, the combination of stationary contacts, contact-bridging means, a rack held to said bridging means, a pinion meshing with said rack, an element rotatable with said pinion in opposite directions, said element being formed with two spaced recesses, a spring-pressed latch adapted to engage in said recesses alternately, a handle rotatable in opposite directions independently of said element, a coiled spring, connections between said spring and the handle and rotatable element for storing power in the spring to rotate said element and pinion when the handle is moved in either direction, a releasing device rotatable with the handle and having a relative rocking movement, and means for rocking said device upon an initial movement of the handle in either direction to position the same to release the latch after a predetermined movement of the handle.

7. In an electric switch, the combination of a swinging switch lever, means for limiting the throw of said lever to and from circuit closing position, reciprocable circuit-closing means, a rack and pinion for reciprocating said circuit-closing means toward and from circuit-closing position, power-operated means for rotating said pinion in either direction, and means controlled by said switch lever for causing said power-operated means to rotate said pinion in opposite directions as the switch lever approaches the opposite limits of its throw.

8. In an electric switch, the combination of stationary contacts, contact bridging means, a rack held to said bridging means, a fixed shaft, a pinion loose on said shaft meshing with said rack, a disk rotatable on said shaft in opposite directions with said pinion and having two spaced notches in its periphery, a spring-pressed pivoted latch lever adapted to engage in said notches alternately, a sleeve rotatable in opposite directions on said shaft independently of said disk, a handle held to said sleeve, a motor spring coiled about said sleeve, connections between said spring and the disk and handle for storing power in said spring to rotate the disk in the direction of rotation of the handle when the handle is moved in either direction, a second disk held to rotate with the sleeve, a releasing lever pivoted intermediate its ends on said second disk, each end of said lever being adapted to move the latch lever out of one of said

notches in the first disk after a predetermined movement of the handle and to be shifted into position to operate the latch by movement of the opposite end of the releasing lever over the latch lever during the initial movement of the handle, and means for releasably holding the releasing lever in its adjusted positions.

9. In an electric switch, the combination of a switch handle rotatable in opposite directions, reciprocable contact-bridging means, stationary contacts, a rack for reciprocating said bridging means, a pinion meshing with said rack, a motor spring adapted to rotate said pinion in either direction, means actuated by movement of the handle in either direction for storing power in said spring, means for normally holding the pinion against rotation, and means for releasing the pinion as the handle approaches the limit of its movement in either direction.

10. In an electric switch of the snap action type, the combination of a swinging switch lever, contact-bridging means, means for limiting the throw of said lever, a motor spring, means actuated by the movement of said lever in either direction to place said spring under tension, means actuated by said motor spring and embodying a rack and pinion for shifting said contact-bridging means toward and from circuit-closing position, means for locking said pinion against rotation, and means movable with said lever for releasing said locking means as the lever approaches the limit of its throw in either direction.

11. In an electric switch, the combination of circuit-closing means, an element rotatable in opposite directions for shifting said circuit-closing means to "on" and "off" positions, a switch handle, power mechanism for rotating said element, a latch for locking said element against rotation in both the "on" and "off" positions of the circuit-closing means, means controlled by the handle for storing power in said mechanism, latch releasing cam means rotatable relatively to said element by the handle, and means for automatically shifting said cam means independently of the handle during successive movements of the handle to present two different parts of said cam means alternately in position to release said latch.

12. In an electric switch, the combination of circuit-closing means, an element rotatable in opposite directions for shifting said circuit-closing means to "on" and "off" positions, a switch handle, power mechanism for rotating said element, a latch for locking said element against rotation in both the "on" and "off" positions of the circuit-closing means, means controlled by the handle for storing power in said mechanism, and latch releasing cam means rota-

table bodily in either direction by the handle relatively to said element and shiftable by engagement with the latch during such rotation to set said cam means in position to release said latch after a further movement of the handle.

13. In an electric switch, the combination of circuit-closing means, an element rotatable in opposite directions for shifting said circuit-closing means to "on" and "off" positions, a switch handle, power mechanism for rotating said element, a latch for locking said element against rotation in both the "on" and "off" positions of the circuit-closing means, means controlled by the handle for storing power in said mechanism, and latch releasing means revolvable in opposite directions by the handle and having cam surfaces at opposite ends thereof, said latch releasing means being shiftable automatically during revolution thereof in either direction by the engagement of one end of the latch releasing means with the latch to present the cam surface at the opposite end of said means in position to release the latch after said releasing means has been revolved a predetermined extent.

14. In an electric switch, the combination of shiftable circuit-closing means, a motor spring, rack and pinion means operable by said motor spring to shift said circuit-closing means to "on" and "off" positions, a latch adapted to automatically lock said circuit-closing means in both its "on" and "off" positions, a switch handle shiftable in different directions, means controlled by said handle for storing power in said motor spring to actuate the rack and pinion mechanism, and cam means revolvable in opposite directions by said handle for releasing said latch after a power storing movement of the handle in either direction.

15. In an electric switch, the combination of shiftable circuit-closing means, a motor spring, rack and pinion means operable by said motor spring to shift said circuit-closing means to "on" and "off" positions, a latch adapted to automatically lock said circuit-closing means in both its "on" and "off" positions, a switch handle shiftable in different directions, means controlled by said handle for storing power in said motor spring to actuate the rack and pinion mechanism, and cam means revolvable in opposite directions by the handle and shiftable automatically independently of the handle by engagement with the latch during movement of the handle in either direction to set said cam means in position to release said latch after a further movement of the handle in the same direction.

16. In an electric switch of the snap-action type, the combination of a motor spring, reciprocable circuit-closing means, means embodying a rack and pinion for projecting

said circuit-closing means with a snap action toward and from circuit-closing position, power-operated means for rotating said pinion in either direction, manually operable means adapted to be rotated in opposite directions, means for limiting the extent of the rotary movement of said manually controlled means in either direction, and means controlled by said manually rotatable means for causing said power-operated means to rotate said pinion in opposite directions as said rotatable means approaches the limits of its rotary movement.

17. In an electric switch of the snap-action type, the combination of contact-brid-

ing means, a coiled motor spring, rotatable means adapted to place said spring under tension when rotated in either direction, means actuated by said motor spring and embodying a rack and pinion for reciprocating said contact-bridging means toward and from circuit-closing position, means for locking said pinion against rotation, and means controlled by said rotatable means for releasing the pinion at the conclusion of the power-storing movement of said rotatable means.

In testimony whereof I hereunto affix my signature.

LOUIS KELLNER.
